UNITED STATES PATENT OFFICE.

JOHN KRUEGER, OF MILWAUKEE, WISCONSIN.

BENDING-MACHINE.

SPECIFICATION forming part of Letters Patent No. 718,478, dated January 13, 1903.

Application filed September 6, 1902. Serial No. 122,321. (No model.)

To all whom it may concern:

Be it known that I, JOHN KRUEGER, a citizen of the United States, and a resident of Milwaukee, in the county of Milwaukee and 5 State of Wisconsin, have invented certain new and useful Improvements in Bending-Machines; and I do hereby declare that the following is a full, clear, and exact description thereof.

10 My invention has for its object to facilitate bending of angle-iron to form flanged rings; and it consists in certain peculiarities of construction and combination of parts herein-after particularly set forth with reference 15 to the accompanying drawings and subsequently claimed.

Figure 1 of the drawings represents a partly-sectional elevation of a machine organized in accordance with my invention to bend angle-iron into a ring having an inner flange, this view being indicated by line 1 1 in the fourth figure; Fig. 2, a similar view of a portion of the machine, illustrating the same organized to bend angle-iron into a ring having an outer 25 flange; Fig. 3, a horizontal section view of said machine, this view being indicated by lines 3 3 in the first figure; and Figs. 4 and 5 transverse sectional views of the aforesaid machine, respectively indicated by lines 4 4 30 and 5 5 in said first figure.

Referring by letter to the drawings, A indicates the bed-plate, B C parallel standards, and D the pillow-block, of a three-roller bending-machine made according to my invention to facilitate the making of flanged rings from angle-iron, said standards being connected by stay-rods b conveniently arranged.

Each of the two parallel lower rollers of 40 the machine is shown as comprising a screw-threaded shaft E, for which standards B C are provided with bearings, a screw-threaded sleeve F, keyed on the shaft, a collar G held by a set-screw c in adjusted position on said 45 shaft to oppose one end of the sleeve, other collars H I, sometimes one and sometimes both, keyed on said sleeve, a nut J, run on the aforesaid shaft against the sleeve end farthest from collar G, and another nut K, run on said 50 sleeve against collar I, all of the collars being of the same diameter.

The upper middle roller of the machine is

shown as comprising a screw-threaded shaft L, shouldered collars M N, loose on the shaft, and set-nuts O, run on said shaft to oppose 55 the outer shoulder ends of the collars. Shaft L is journaled in heads P, having vertically-adjustable shanks Q, and a preferably tapered end of said shaft turns in a block R, suspended from a screw S, that turns in the upper transverse portion of a yoke T, bolted at its ends on the pillow-block of the machine. The shanks Q of heads P have their play in the standards of the machine and lower round 60 ends of these shanks are screw-threaded. Engaging the screw-threaded ends of shanks Q are nuts U, that turn in plates d, bolted to lugs e of the machine-standards, and lower plate-opposing flanges f of the nuts prevent them from moving up on said shanks. A 70 bevel gear-wheel V is made fast on each nut U by a set-screw g or otherwise to have its hub rest on the adjacent plate d, whereby descent of said nut on the shank engaging same is prevented. The machine-standards 75 are provided with bearings h for spindles W, and fast on these spindles are bevel-pinions X and hand-wheels Y, the pinions being in mesh with the bevel gear-wheels aforesaid.

One of the shanks Q is in sections on a 80 pivot t in order that its upper portion may be swung clear of a journal of the roller-shaft L, for which the head of said shank serves as a bearing.

The machine is provided with a main or 85 pulley shaft Z, and by means of a gear-train common in three-roller bending-machines motion is imparted from said shaft to the lower rollers.

When the machine is organized for bending angle-iron into rings having inner flanges, the collar H pertaining to each lower roller is omitted and the collars G I adjusted to provide space on the sleeve F for the horizontal portion of the angle-iron. By adjustment of 95 the set-nuts O of the upper roller the collars M N of this roller are brought in position to catch the vertical portion of the angle-iron between their inner sides, and by manipulation of the screw S and spindles W said upper roller is adjusted to have said collars thereof impinge against said horizontal portion of said angle-iron, vertical adjustment 100 of the aforesaid upper roller being also pro-

portionate to the diameter of the ring that results from an operation of the machine. Either L or L iron may be bent on the machine and two L-irons placed web to web to form a L may be bent at the same time, the result being two rings each having an inner flange. To bend angle-iron into rings having outer flanges, collar H is put on sleeve F to abut the inside of collar I and said sleeve and collar G are adjusted with reference to each other to leave an intervening space in which to catch the vertical portion of the angle-iron, the horizontal portion of said angle-iron being supported on the collars G H under the collars M N of the upper roller, adjusted as shown in Fig. 2. A ring having been bent on the machine, the upper roller is adjusted to clear said ring and the upper section of the adjustable jointed shank, terminating in a bearing for a journal of the roller-shaft, is swung out, said roller being then supported by the other adjustable bearing and block with which said shaft thereof has engagement.

Having thus described my invention, what I claim as new, and desire to secure by Letters Patent, is—

1. A bending-machine having parallel rollers each comprising a shaft in stationary bearings, a collared sleeve and a collar adjustable on the shaft but held to turn therewith; another roller intermediate of those aforesaid on a higher plane and comprising a shaft in vertically-adjustable bearings one of which has a jointed shank, collars loose on the latter shaft and collar-opposing set-nuts adjustable on the same shaft; a drive-shaft, and a gear-train connecting the drive-shaft and parallel-roller shafts.

2. A bending-machine having a pair of parallel rollers each comprising a screw-threaded shaft in stationary bearings, a collar adjustable on the shaft but held to turn therewith, a screw-threaded sleeve in key connection with the shaft, two collars one or both of which have key connection with the sleeve, a collar-opposing nut on said sleeve, and a

sleeve-opposing nut on said shaft; another roller intermediate of those aforesaid on a higher plane and comprising a screw-threaded shaft in vertically-adjustable bearings one of which has a jointed shank, collars loose on the latter shaft and collar-opposing set-nuts adjustable on the same shaft; a drive-shaft, and a gear-train connecting the drive-shaft and parallel-roller shafts.

3. A bending-machine having parallel rollers each comprising a shaft in stationary bearings, a collared sleeve and a collar adjustable on the shaft but held to turn therewith; another roller intermediate of those aforesaid on a higher plane and comprising a shaft in vertically-adjustable bearings one of which has a jointed shank, collars loose on the latter shaft and collar-opposing set-nuts adjustable on the same shaft; a vertically-adjustable block engaged by the end of the middle roller-shaft farthest from the bearing for same that has the jointed shank, a drive-shaft, and a gear-train connecting the drive-shaft and parallel-roller shafts.

4. A bending-machine having parallel rollers each comprising a shaft in stationary bearings, a collared sleeve and a collar adjustable on the shaft but held to turn therewith; another shaft intermediate of those aforesaid on a higher plane and comprising a shaft in bearings having screw-threaded shanks one of which is jointed, collars loose on the roller, and collar-opposing set-nuts adjustable on the same shaft; nuts held against travel on the bearing-shanks, means for rotating these nuts, a drive-shaft, and a gear-train connecting the drive-shaft and parallel-roller shafts.

In testimony that I claim the foregoing I have hereunto set my hand, at Milwaukee, in the county of Milwaukee and State of Wisconsin, in the presence of two witnesses.

JOHN KRUEGER.
